UNITED STATES PATENT OFFICE

JOHN C. F. HORSTMANN, OF BROOKLYN, NEW YORK

POOL-BALL-RACKING FRAME

Application filed September 24, 1927. Serial No. 221,721.

This invention relates to pool ball supporting frames, adapted particularly for use in connection with pocket pool tables.

The primary object of the invention is to provide a triangle to contain the pool balls which snugly accommodates the requisite number of balls and maintains them properly until it is desired to "spot" them upon the table.

10 A further object is to provide a frame of this character, usually of triangular form, and which may constitute an efficient means whereby the balls may be carried from place to place or maintained in proper racked form when not in use upon the table.

15 A further object is to provide a pool ball racking triangle by the use of which it becomes unnecessary in supporting the balls to oscillate the frame as is customarily done 20 prior to removal of the triangle from the assembled balls.

25 A still further object is to provide a ball racking triangle adapted particularly for use in connection with the pool table attachment described and claimed in my copending application, Serial No. 221,720, filed September 24, 1927.

With these objects in view, together with others which will appear as the description 30 proceeds, the invention consists in the novel construction, combination and arrangement of parts, all as will be described more fully hereinafter, illustrated in the drawings, and particularly pointed out in the claims.

35 Fig. 1 is a plan view of a pool ball racking triangle constructed in accordance with my invention and showing the same as it will appear with the balls applied thereto and ready to be "spotted" upon the table,

40 Fig. 2 is a rear elevation of the frame, and

Fig. 3 is a transverse sectional view taken substantially upon line 3-3 of Fig. 1 with the balls removed.

In carrying out the invention, a conventional form of triangle 4 may be employed,

and as usual, such a rack comprises an equilateral triangle of a size to snugly accommodate fifteen pool balls. The sides of this triangle may be secured together in any desired or preferred manner and are connected at the corners by any suitable means, the usual blocks 5 being shown in the present instance. This triangle is provided in each of its three sides with slots indicated at 6. These slots extend approximately throughout the operative length of the sides of the triangle, and near the lower edges of said sides. All of said slots are positioned in a common plane.

Associated with the triangle is a removable slide or bottom 7, constituting a flat plate preferably of rectangular formation, and of a breadth substantially equal to the length of any one of said slots. This plate, for convenience in operation, may be a trifle thinner than the breadth of said slots, and has applied to the upper surface thereof a layer 60 of fabric such as a cushioning felt or pad 8. The length of this plate or bottom is substantially equal to the altitude of the triangle so that when inserted through a slot in the base and to its limit of movement, the forward edges of the bottom will project through the slots in the sides of the triangle. The bottom, therefore, will be supported in proper position within the triangle within the slots 65 70 75 in the base as well as the sides.

The slide bottom is provided upon its upper surface and near one edge with a cleat 9 secured in any preferred manner to the base, and the under side of this cleat is recessed as at 9' to constitute a finger grip. That portion of the bottom underlying said recess is cut away as at 10 to further facilitate application of the fingers to the underside of the cleat. This cleat constitutes not only 80 efficient means for manipulating the slide bottom, but also operates as a limiting or stop member for the slide bottom.

In practice, the triangle is rested upon its edges with the slide bottom 7 inserted to the 85 90

full limit of its movement, whereupon said bottom will be held within the several slots in parallelism with the edges of the triangle. The balls 11 are then placed therein in the usual way, resting upon the slide bottom 7. When thus positioned, the triangle may be carried about with the balls properly positioned therein, and by reason of the location of the slide bottom near the lower edge of the frame, the centers of gravity of the several balls will be positioned approximately at the upper edge of the triangle. This arrangement permits of considerable latitude of tilting of the triangle without danger of the balls dropping out. When it is desired to "spot" the balls, the triangle with the balls so assembled is placed properly upon the pool table with the ball at the vertex disposed over the table spot. When so positioned, the triangle is held with one hand while the slide bottom 7 is withdrawn with the other, whereupon the balls drop to the table in proper assembled triangular formation. The triangle may then be removed from the balls and the slide bottom replaced therein ready for the next racking operation. By reason of the uniformity of the slot sizes in the three sides of the triangle, the plate or slide bottom may be used with any of said sides as the base of the triangle, and the surface of the slide bottom is sufficiently large to constitute a bottom for the support of all the balls.

As heretofore stated, this frame is adapted particularly for use in connection with the pool table attachment described in my application for Letters Patent aforesaid, but it will be understood that its use is not necessarily restricted to that type of table, as it may equally as well be used with tables not equipped with runways for the balls. By constructing the frame in this manner it is at once apparent that the balls may be racked and properly supported without resorting to the oscillating movements of the triangle commonly employed with the ordinary type of triangle.

While the foregoing is a description of the invention in its preferred embodiment, it is nevertheless to be understood that variations in the construction and assemblage of parts may be liberally resorted to if desired within the limitations of the appended claims.

Having thus described my invention, I claim:

- 55 1. In a ball rack, a frame comprising an equilateral triangle having slots of uniform length and breadth in its three sides, the said slots terminating equal distances from the ends of their respective sides, a slide bottom 60 of a breadth substantially equal to the length of any one of said slots and adapted to enter the same, and edges of said slide adapted to enter the other of said slots.
- 65 2. In a ball rack, a frame comprising an equilateral triangle having slots of uni-

form length and breadth in its three sides, a slide comprising a flat plate of a breadth equal to the length of one of said slots, said plate being of rectangular shape and of a length substantially equal to the altitude of said triangle, a block at one end of said plate having a recess in its lower edge to constitute a finger grip, and a soft covering for said plate.

In testimony whereof I affix my signature. 75
JOHN C. F. HORSTMANN.
